RONALD F. McFEELY, OF BEVERLY, MASSACHUSETTS, ASSIGNEE TO UNITED SHOE MACHINERY COMPANY, OF PATERSON, NEW JERSEY, A CORPORATION OF NEW JERSEY.

LASTING-MACHINE.

1,162,704.

Specification of Letters Patent. Patented Nov. 30, 1915.

Application filed September 23, 1914. Serial No. 863,130.

To all whom it may concern:

Be it known that I, RONALD F. McFEELY, a citizen of the United States, residing at Beverly, in the county of Essex and State of Massachusetts, have invented certain Improvements in Lasting-Machines, of which the following description, in connection with the accompanying drawings, is a specification, like reference characters on the drawings indicating like parts in the several figures.

This invention relates to lasting machines, and particularly to toe lasting mechanism, and has for its object to increase the capacity and improve and simplify the construction of mechanism for lasting the toes of shoes on right and left crooked lasts.

For many styles of shoes right and left wipers must be provided to fit the different contours of the toe portions of the lasts for the right and left feet. It has previously been proposed to equip a toe lasting mechanism with two pairs of toe embracing wipers and mount the head for adjustment, as for example for rotation, to bring either pair of wipers into position to operate on a shoe, but, partly at least, because of the complication and bulkiness of such a mechanism the practice is still followed almost entirely of taking out one pair of wipers and substituting a pair adapted for the other foot when changing from right to left shoes. This consumes time and creates a need for a wiper fastening which, while being secure, can be quickly manipulated by a shoemaker without the aid of tools. Also this practice of changing wipers, in order to reduce loss of time, makes necessary to last first a series of shoes for one foot and then the mates to those shoes. It is impractical, except on sample work, to take the time to change wipers and last mates alternately. This is a disadvantage because obviously the best results are obtained by lasting mates successively and matching them.

An important feature of the present invention consists in an end lasting mechanism comprising two pairs of end embracing wipers and operating mechanism by which either pair can be used. In the illustrated embodiment of the invention the pairs of wipers are

superposed with one pair in sliding contact with the other and one pair has an acting edge shaped to fit a right shoe toe and the other pair has an acting edge to fit a mating 55 left shoe toe.

A further feature of the invention consists in adjusting means for rendering end embracing wipers operative or inoperative. As herein shown, a single adjusting means is 60 connected with two pairs of wipers and can be manipulated to render either pair of wipers available for use alternatively. The other pair is, as shown, simultaneously adjusted to a position where those wipers will offer 65 no obstruction to use of the operative pair.

Another feature of the invention consists in a single operating means by which either of two pairs of wipers may be used alternatively. This means is shown as a hand 70 lever having, through adjusting means and duplex connections, an operative control of the wipers by which either pair of wipers alternatively can be caused to embrace a shoe end and wipe the upper into lasted position. 75 The adjusting means is shown as an eccentric by which said duplex connections are movable relatively to the operating bar to retract one pair of wipers to a position where they will be inoperative for engaging 80 a shoe and to advance the other pair of wipers to a position where they can be used to the exclusion of the retracted pair.

The illustrated embodiment of this invention has the advantage that it provides a toe 85 lasting mechanism which is not greatly dissimilar in arrangement and mode of operation from the toe lasting mechanism with which operators are familiar in the commercial lasting machine now in general use and 90 which by one simple adjustment of an eccentric, having a lever handle, can be made to present for use the wipers for lasting either a left or a right shoe. By the use of this invention it is practical to last the toes of 95 right and left mates successively because that can be done without appreciable loss of time.

These and other features of the invention will appear from the following description 100 and accompanying drawings of a preferred embodiment of the invention, and the inven-

tion will then be particularly pointed out in the claims.

Figure 1 is a perspective view of the toe lasting mechanism of a lasting machine, of the commercial type referred to, when equipped with a preferred embodiment of this invention. Fig. 2 is a plan view of the same. Fig. 3 is a section on line 3—3 of Fig. 2 partially broken away and extended to show an operative relation of one pair of wipers to a shoe.

The illustrated machine is like the said commercial machine, which is shown in United States Letters Patent No. 1,018,477 granted February 27, 1912 on application of Matthias Brock, in that it comprises means including the toe rest 2 for supporting a shoe; a holddown 3 for clamping the toe down on the rest, and a toe lasting head 10 mounted for vertical movement in the machine frame by a treadle 4 for causing the wipers to rub up the sides of the shoe toward its bottom edge line after they have been closed to embrace the toe below the 25 edge line of the shoe. The treadle is double-ended so that it can be made to depress the wipers after they have been closed in over the shoe bottom whereby the wiped over margin of the upper materials are 30 compressed upon the margin of the shoe inner sole. A single hand lever 5 is employed for imparting the opening and closing movements to the toe embracing wipers, and there are the usual adjusting devices 6 and 35 7 for rocking the wipers about the longitudinal axis of the shoe bottom to adapt their position to the "roll" of the last bottom and for tipping the wipers about a transverse axis to accommodate the "pitch" 40 of the last bottom.

Two pairs of wipers 10 and 11 are provided, each pair having an edge contour shaped to embrace completely the toe portion of a shoe, one pair preferably being 45 shaped for a right shoe and the other for the left shoe of the same style, that is, for the mate to the right shoe. The pairs of wipers are superposed one on the other and preferably in sliding contact with each 50 other. Each pair of wipers 10, 11 has its own carrier plates 12 and 13 to which the wipers are detachably secured so as to permit substitution of different styles of wipers when the style or shape of the shoe to be 55 lasted is changed. Each wiper carrier has long cam slots 14 which receive stationary guide rolls 15. These guide rolls for the upper and lower wipers may be the same and be secured in the underlying plate 16 60 of the wiper carriage, or the rolls for the two pairs of wipers may be separate and those for the upper wipers be suspended from the cover plate 17 of the carriage. It will be noted that in either case the cover

plate confines the wiper carriers 12, 13 with 65 a close sliding fit within the carriage so that both pair are responsive to lifting and depressing movements imparted by the treadle 4 without any lost motion.

The pairs of wiper carriers 12, 13 are 70 connected by links 18, 19 respectively to the cross-bars 20, 21 of plungers 22, 23 which extend to the wiper operating lever 5. For convenience these plungers are half cylindrical rods, Fig. 3, fitted together to turn 75 upon a common axis located between them in response to adjustment by the adjusting device 6. The connection between the plungers 22, 23 and the operating lever 5 comprises heads 24, 25 on the plungers which 80 have transversely elongated slots which receive the connecting stud 26 which depends from the lever. The connecting stud 26 carries two oppositely faced eccentrics 28, 29, Figs. 2 and 3, located respectively in the 85 slotted heads 24, 25 of the plungers. The stud also has an adjusting lever 30 by which it can be turned and the eccentrics 28, 29, acting through the plungers 22, 23, thereby made to adjust the pairs of wipers one back- 90 wardly and the other forwardly. This adjustment for example will advance the upper pair of wipers 10, which may be assumed to be the wipers for the right last, forwardly toward the shoe support 2 and 95 into operative position, and simultaneously will retract the lower pair of wipers 11 to a position more remote from the shoe support 2 and into a position where they will offer no obstruction to the use of the upper 100 wipers 10 in all of the manipulations which it is customary for an operator to make in lasting a shoe toe in said commercial lasting machine. By oppositely swinging the lever 30, stud 26 and eccentrics 28, 29 the 105 upper pair of wipers will be withdrawn and the lower pair will be advanced to position for use. A spring pin 32 in the end of the adjusting lever 30 is adapted to enter a recess 31 in the operating lever 5 at either 110 side of the connecting stud 26 and maintain the adjustment with either pair of wipers in position for use to the exclusion of the other pair.

The adjustment to present either the right 115 or the left pair of wipers for use can be made instantaneously so that it is just as convenient to last the toes of the right and then the left of a pair of shoes successively as it is to last a series of right toes and then a 120 series of left toes, with the obvious advantage gained by lasting the mates of a pair of shoes successively, with opportunity to compare them and ascertain that both shoes have been made to look alike so that the appearance of the pair shall be as desired. Substantially all of the time heretofore required for changing wipers is thus saved 125

and there is no need for an operator to give time or attention to consider whether he is picking up a right or a left shoe for lasting because he can instantly and with perfect convenience present to the shoe, after it is jacked in the machine, the pair of wipers needed for lasting the toe of that shoe.

Having explained the nature of this invention and described a preferred embodiment thereof, I claim as new and desire to secure by Letters Patent of the United States:—

1. A right and left toe lasting mechanism having, in combination, two complete pairs 15 of toe embracing plates arranged one above the other, one pair having an edge contour adapted to the toe of a shoe for one foot and the other pair having a different edge contour adapted to the toe of the other foot, 20 each pair being movable substantially in its plane of operation out of operative position and into a position where it will not interfere with the use of the other pair in lasting the toe portion of a shoe, and means for 25 operating said pairs of plates to do their work.

2. A right and left toe lasting mechanism having, in combination, a carrying head mounted to present at all times the same 30 side uppermost and the same end toward the shoe, and upper and lower end embracing lasting plates mounted in said head, one set of plates being formed to wipe an upper into lasted position over the bottom of a right 35 shoe toe and the other set of plates being formed to wipe an upper into lasted position over the bottom of a left shoe toe, and means for operating said plates to last either a right or a left shoe toe.

3. A right and left end lasting mechanism having, in combination, end embracing plates having an edge contour adapted to wipe into lasted position an upper over the end of a last for one foot, end embracing 45 plates superposed on the first plates and having an edge contour adapted to wipe into lasted position an upper over the end of a last for the opposite foot, and operating means by which the end embracing plates 50 for one foot can be retracted to a position where they will be out of the way of the use of the plates for the other foot and the plates for said other foot can be used to do their work.

4. An end lasting mechanism having, in combination, two pairs of end embracing wipers, one pair being superposed on the other and having an edge contour adapting them to wipe into lasted position an upper 60 over a last having a shape differing from that for which the other pair of wipers is adapted, and operating mechanism by which either pair of wipers may be used alternatively.

5. An end lasting mechanism having, in combination, two complete sets of end embracing plates of which one set is superposed on the other, each set of plates being mounted for advancing and turning movement to close and open relatively to a shoe 70 end and having an edge contour differing from that of the other set, a shoe end support, and means by which said end embracing plates and said support can be relatively moved to present the shoe bottom and the 75 lower face of either set of plates in suitable relation for the plates to wipe an upper into lasted position over the shoe bottom.

6. In a machine of the class described, an end lasting mechanism comprising two pairs 80 of superposed toe embracing plates, each pair of plates completely embracing the toe and being mounted for combined advancing and turning movement to close and open relatively to a shoe end to wipe the shoe upper 85 inwardly over the feather of a welt shoe innersole, the edges of said two pairs of plates being of different curvature to adapt them respectively to right and left shoe toes, and operating means by which either pair 90 of toe embracing plates may be used upon the shoe for which they are adapted to the exclusion of the other pair.

7. An end lasting mechanism having, in combination, two complete pairs of end embracing wipers arranged one pair above the other and shaped respectively for right and left lasts of the same style, shoe positioning means, means for moving the wipers together up and down to bring either pair into 95 operative relation to the plane of the shoe determined by said positioning means, and means for operating either pair of wipers which may be in operative relation to the shoe to work the upper over the last bottom. 100

8. An end lasting mechanism having, in combination, two complete sets of toe embracing plates arranged with one set above the other and one set having a different edge 110 contour from the other to adapt it to embrace and snugly fit a shape different from the shape which the other fits, and operating means for said plates arranged to impart to one set of plates toe embracing movements 115 relatively to the other set of plates.

9. A right and left end lasting mechanism having, in combination, two pairs of wipers, a single operating lever and adjusting means by which either pair of wipers can be used 120 to the exclusion of the other pair by manipulation of said operating lever.

10. A right and left end lasting mechanism having, in combination, two pairs of wipers, a single operating lever and adjusting means between said lever and said pairs of wipers by which either pair of wipers can be made available for use alternatively. 125

11. A right and left end lasting mechanism having, in combination, two pairs of wipers, a single operating lever and adjusting means by which one pair of wipers can be advanced to position for use and the other pair retracted to a position where they will offer no obstruction to use of the other pair. 65
12. A right and left end lasting mechanism having, in combination, two pairs of wipers, a single operating lever and adjusting means by which either pair of wipers alternatively can be made by said lever to embrace a shoe end and wipe the upper into lasted position. 70
13. A right and left end lasting mechanism having, in combination, two pairs of wipers, a single operating lever, duplex connections extending from said pairs of wipers to said lever, and adjusting means for determining which connections shall impart to its pair of wipers operative movements adapted for lasting a shoe. 75
14. A right and left end lasting mechanism having, in combination, two pairs of wipers, a single operating lever, duplex connections extending from said pairs of wipers to said lever, and adjusting means by which one pair of said wipers can be retracted to where they will remain in an inoperative relation to the shoe while the other pair are being used by manipulation of the operating lever. 80
15. A right and left end lasting mechanism having, in combination, two pairs of wipers, a single operating lever, duplex connections extending from said pairs of wipers to said lever, and adjusting means by which one pair of said wipers can be advanced to position for lasting a shoe while the other pair remain in a position where they offer no obstruction to the use of the operative pair. 85
16. A right and left end lasting mechanism having, in combination, two pairs of wipers, a single operating lever, duplex connections extending from said pairs of wipers to said lever, and means by which one pair can be adjusted to operate to the exclusion of the other pair. 90
17. A right and left end lasting mechanism having, in combination, two pairs of wipers, a single operating lever, duplex connections extending from said pairs of wipers to said lever, and a double eccentric by which either pair of wipers can be adjusted to operate to the exclusion of the other pair. 95
18. A right and left end lasting mechanism having, in combination, two superposed pairs of wipers, a wiper carrier in which said wipers are mounted, and an operating lever and connections by which either pair of wipers can be used for lasting to the exclusion of the other pair. 100
19. A right and left end lasting mechanism having, in combination, two superposed pairs of wipers, an operating lever and an adjuster by which to cause either pair of wipers to be used to the exclusion of the other pair. 105
20. A right and left end lasting mechanism having, in combination, two superposed pairs of wipers, a wiper carrier in which said wipers are mounted, and means for adjusting one pair of wipers to an inoperative position in said carrier while the other pair may be used. 110
21. A right and left end lasting mechanism having, in combination, two superposed pairs of wipers, a wiper carrier in which said wipers are mounted, and means for rendering either pair of wipers operative alternatively. 115
22. A machine of the class described having, in combination, means for supporting a shoe for lasting, two complete, separate pairs of end embracing wipers both facing the shoe on said support, operating means for the wipers, and means permitting either pair of wipers to be made operative upon the shoe to the exclusion of the other pair after the shoe has been positioned for lasting. 120
23. A right and left end lasting mechanism having, in combination, two pairs of end embracing wipers, an adjusting means for the wipers which can be shifted to present for use either pair of end embracing wipers, and one operating means constructed and arranged to operate either pair of wipers which is presented for use. 125
24. A right and left end lasting mechanism having, in combination, two pairs of wipers, an operating lever, duplex connections extending from said pairs of wipers to said lever and adjusting means by which either pair of wipers alternatively may be made operative for lasting a shoe by lever movement transmitted through said connections. 130
25. A right and left end lasting mechanism having, in combination, two pairs of end embracing wipers arranged one pair over the other, operating means therefor, and an adjusting means for the wipers which can be shifted to present for use either pair of end embracing wipers. 135
26. A right and left end lasting machine having, in combination, two separate sets of superposed wipers each of which is constructed and arranged to embrace a shoe toe completely, and means by which one of said sets of wipers can be adjusted to a retracted position permitting the use of the other pair exclusively for lasting a shoe toe. 140
27. A right and left end lasting machine having, in combination, two separate sets of superposed wipers each of which is con- 145

structed and arranged to embrace a shoe toe completely, one of said sets of wipers being adjustable relatively to the other forwardly and backwardly to and from an operative position, and operating means for said wipers.

In testimony whereof I have signed my

name to this specification in the presence of two subscribing witnesses.

RONALD F. McFEELY.
